UNITED STATES PATENT OFFICE.

PATSY PARISO, OF ELMIRA, NEW YORK.

RAIL CONNECTION.

Application filed July 23, 1925. Serial No. 45,652.

This invention appertains to novel means for connecting the adjacent ends of a pair of members together so as to produce a strong and rigid joint.

5 A primary object of the present invention is to provide a novel rail joint having the meeting ends of the rail sections provided with diagonal faces having intermeshing teeth formed thereon, the arrangement 10 of the faces allowing the weight of the railroad rolling stock passing over the rails to be borne directly by the rail at the joint instead of by the fish plates, the teeth forming means for preventing longitudinal 15 movement of the rail sections relative to one another.

A further object of the invention is to provide a novel rail joint having the adjacent ends of the rail sections provided with 20 diagonal faces filed or otherwise treated to provide intermeshing alligator teeth, the sections being united by the conventional fish plates for preventing lateral shifting movement of the said rail sections relative 25 to one another.

A further object of this invention is to provide a novel rail joint of the above character, which will effectively unite the rail sections and eliminate noise incident to the 30 rolling stock passing over the joint, and which will be durable and efficient in use, one that will be simple and easy to manufacture.

With these and other objects in view, the 35 invention consists in the novel construction, arrangement and formation of parts, as will be hereinafter more specifically described and claimed, and illustrated in the accompanying drawings, in which drawings:

40 Figure 1 is a side elevation showing a pair of rail sections with their meeting ends constructed in accordance with this invention,

Figure 2 is a top plan showing the complete rail joint,

Figure 3 is an end elevation of one of the rail sections, showing the same constructed in accordance with the invention.

Referring to the drawings in detail, 50 wherein similar reference characters designate corresponding parts throughout the several views the letters A and B generally indicate a pair of rail sections, which embody the conventional ball or tread 5, base flanges 6, and connecting web 7. The con-

necting web 7 of each rail section adjacent to the junction of the sections A and B is provided with suitable bolt holes.

The meeting faces of the rail sections A and B are arranged at an angle to the transverse axis of the rails, preferably at an angle of forty five degrees so that the said inclined faces will overlap when the sections A and B are connected together. The inclined faces indicated by the reference character 8 of the rail sections A and B are milled or otherwise treated to provide vertically extending alligator teeth 9 and 10 respectively which are adapted to intermesh, when the rail sections A and B are united. 70 Each of the inclined faces 8 and the interlocking teeth 9 and 10 also prevent undue strain on the fish plates 11 which are utilized for connecting the sections together and thus prevent breakage of said fish plates. 75 The fish plates 11 can be of the usual character and suitable bolts 12 are passed through the fish plates and through the bolt openings in the rail sections A and B. The fish plates 11 are utilized more particularly in the present invention to prevent the lateral shifting of the rail sections A and B relative to one another. 80

From the foregoing description, it can be seen that I have provided a novel rail joint 85 in which an improved means has been provided for connecting a pair of rail sections together.

Changes in details may be made without departing from the spirit or scope of this 90 invention, but:

What I claim as new is:

A railroad joint comprising a pair of rail sections each including a web, a ball and base flanges, the meeting ends of the rail sections being provided with faces arranged at an incline to the transverse center of the rail sections to permit the overlapping of said rail sections, pointed angularly extending alligator teeth formed on 95 said faces extending from one end thereof to the other adapted to intermesh when the rail sections are connected, the teeth extending vertically from the base flanges to the balls of said rail sections, and fish plates 100 connecting the sections together on opposite sides of the joint.

In testimony whereof I affix my signature.

PATSY PARISO.
